Patented Dec. 17, 1968

212,939

TRUCK BUMPER

Paul B. Nunn, 3200 SW. 59th St.,
Oklahoma City, Okla. 73119

Filed Dec. 4, 1967, Ser. No. 9,629

Term of patent 14 years

(Cl. D14—6)

FIGURE 1 is a plan view of a truck bumper illustrating my new design.

FIGURE 2 is an elevation view of the truck bumper depicted in FIGURE 1 as the bumper appears when viewed from the rear of a truck on which it is mounted.

FIGURE 3 is an elevation view of the truck bumper depicted in FIGURES 1 and 2 as the bumper appears when viewed from the opposite side thereof from that illustrated in FIGURE 2.

FIGURE 4 is an end elevation view of the truck bumper depicted in FIGURE 1.

FIGURE 5 is a sectional view taken along line 5—5 of FIGURE 1.

FIGURE 6 is a sectional view taken along line 6—6 of FIGURE 1.

I claim:

The ornamental design for a truck bumper, as shown.
